UNITED STATES PATENT OFFICE

WILLIAM T. BRADBURY, OF KANKAKEE, ILLINOIS, ASSIGNOR TO FLORENCE STOVE COMPANY, OF BOSTON, MASSACHUSETTS, A CORPORATION OF MASSACHUSETTS

DESIGN FOR A CABINET FOR OIL BURNER SUPPLY TANKS

Application filed April 26, 1933. Serial No. 47,906. Term of patent 7 years.

To all whom it may concern:

Be it known that I, WILLIAM T. BRADBURY, a citizen of the United States, residing at Kankakee, in the county of Kankakee and State of Illinois, have invented a new, original, and ornamental Design for a Cabinet for Oil Burner Supply Tanks, of which the following is a specification, reference being had to the accompanying drawing forming part thereof.

The figure is a perspective view of the cabinet showing my new design.

I claim:

The ornamental design for a cabinet for oil burner supply tanks, substantially as shown.

WILLIAM T. BRADBURY,
